UNITED STATES PATENT OFFICE.

VICTOR CAROUSO, OF OAKLAND, CALIFORNIA.

BATTERY SWITCH-LOCK.

1,393,259.

Specification of Letters Patent. Patented Oct. 11, 1921.

Application filed January 24, 1920. Serial No. 353,870.

To all whom it may concern:

Be it known that I, VICTOR CAROUSO, a citizen of the United States, residing at Oakland, in the county of Alameda and State of California, have invented certain new and useful Improvements in Battery Switch-Locks, of which the following is a specification.

My invention is a battery switch lock particularly useful for locking the ignition and lighting and starting circuit of an automobile out of operation.

Referring to the annexed drawing which forms a part of this specification:

15 Figure 1 is a side view of my lock.

Fig. 2 is a rear view thereof.

Fig. 3 is a cross section of my lock taken on line 3—3 of Fig. 1 looking toward the front of the lock.

20 Fig. 4 is a cross section of my lock taken on line 3—3 of Fig. 1 looking toward the rear of the lock.

Fig. 5 is a diagrammatic view of an automobile ignition and lighting circuit controlled by my switch.

In the drawing 1 indicates a front plate and 2 a rear plate which are connected by four rods 3 spaced apart at points corresponding to the corners of the plate 2.

30 Two socket switch contacts 4 are mounted on the inside of the plate 2, from the rear of which contacts extend binding posts 5 through openings 6 in said plate. Insulating bushings 7 fit in the openings 6, and have flanges

35 8 which engage the inner surface of plate 2, the binding posts 5 extending through said bushings with the inner end of the socket contacts 4 engaging said flanges. Washers 9 of insulation fit on the binding posts 5

40 against the rear surface of the plate 2. Nuts 10 screw on binding posts 5 against the washers 9. The wire terminals 11 are clamped on the binding posts 5 between the nuts 10 and nuts 12 which screw on said binding posts against said terminals.

A stud 13 which extends through the upper part of front plate 1 is slidably mounted in a bearing 14 on said plate and carries on its rear end a bus bar 15 which

in turn carries two rearwardly extending 50 switch contact pins 16 in alinement with sockets 4. A head 17 is secured on the front end of stud 13.

In the lower part of the front plate 1 is mounted a standard Yale lock 20 having a 55 swinging arm 21 in the rear thereof, the end of which is adapted to swing in the rear of the bus bar 15. A pin 22 projects forwardly from the plate 2 directly in the rear of arm 21 to engage said arm to prevent forcing of 60 the lock.

To one pole of the battery 30 of an automobile ignition and lighting and starting system is connected a lead 31 which connects to the terminal 11 of one contact 4. A lead 65 32 connects the other pole of said battery and one brush of a motor generator 33. A lead 34 is connected to the other brush of said motor generator and to the terminal 11 of the other socket contact 4. Lamps 35 are 70 connected in parallel to the lead 34.

By pushing the stud 13 inwardly the pins 16 are introduced into the socket contacts 4, closing the switch. Said pins are pulled out of said socket contacts and the switch 75 opened by pulling said stud outwardly. By means of a key 40 the lock arm 21 may be swung in the rear of bus bar 15, in which position the forward end of pin 22 is just behind the arm, thus locking the switch 80 open. The arm 21 may be swung out of the path of bus bar 15 by said key to unlock the switch.

Having described my invention, I claim:

A switch lock including a front and a rear 85 plate connected together, socket contacts on said rear plate, a stud reciprocatively mounted in said front plate, a bus bar mounted on said stud, pins on said bus bar in alinement with said socket contacts, and a lock mounted on said front plate, said lock including a swinging arm adapted to be swung into the path of said bus bar to prevent the introduction of said pins into said socket contacts. 90

95 In testimony whereof I affix my signature.

VICTOR CAROUSO.
